UNITED STATES PATENT OFFICE.

JOHN SCHEDLER, OF PHILADELPHIA, PENNSYLVANIA.

BOTTLE STOPPER.

Application filed March 31, 1921. Serial No. 457,356.

To all whom it may concern:

Be it known that I, JOHN SCHEDLER, a citizen of the United States, residing at Philadelphia, in the county of Philadelphia and State of Pennsylvania, have invented certain new and useful Improvements in Bottle Stoppers, of which the following is a specification.

One object of my invention is to provide an improved stopper which will more completely seal the necks of bottles or other containers than stoppers made prior to my present invention.

Another object of my invention is to make my improved stopper of such construction that it can be cheaply and quickly manufactured and so that it can be easily and quickly attached to or removed from a bottle.

These objects, and other advantageous ends which will be described hereinafter, I attain in the following manner, reference being had to the accompanying drawings in which—

Figure 1 is a top plan view showing my improved stopper applied to a bottle.

Figure 2 is a fragmentary section taken on the line 2—2 of Figure 1.

Figure 3 is a section taken on the line 3—3 of Figure 2.

Figure 4 is a view of the same general character as shown in Figure 3, illustrating the parts before they are moved into their clamping positions, and

Figure 5 is a developed view showing a blank which can be stamped out of sheet metal and afterwards bent to form the clamping lever illustrated in Figures 1 to 4 inclusive.

Referring to the drawings, 6 represents the neck of a bottle. My improved stopper includes a soft rubber nipple 7 having a cylindrical sleeve 8 adapted to be projected into the throat 9 of the bottle neck 6. The

sleeve 8 at its top has an annular integral flange 10 which is adapted to abut the top surface 11 of the bottle neck. A disk 12 has a diametrically extending slot 13; the slot having parallel side walls. This disk

is adapted to rest upon the top of the flange 10 of the nipple 7 and is of a greater diameter than the diameter of the throat 9 at the top surface 11 so that by pressing downwardly upon the disk 12 the rubber of the flange 10 will be compressed firmly against

the top surface 11 and will thereby form a seal.

A member 14, which is preferably made in the form of a metallic link, is adapted to be inserted through the slot 13 in the disk 12 so as to extend partway into the sleeve 8. This link has an upper yoked end 15 in the form of a loop and a lower hooked end 16. One side 17 of the link is continuous and joins the yoked end 15 with the hooked end 16. The other side 18 of the link is separated to provide a space 19 between the upturned end 20 of the hooked portion 16 and the lower end of the side 18, as clearly shown in Figures 3 and 4. The side 17 has lugs 21 projecting inwardly at different levels for a purpose hereinafter described.

A tapered spreading plug 22, which is preferably made frusto-conical and of a hard substance such as metal, has an eyelet 23 adapted to be hooked over the upturned end 20 so as to hang in the hooked portion 16 of the link. This plug 22 has its uppermost portion of smaller diameter than the internal diameter of the sleeve 8 and its larger portion at the bottom of greater diameter than the internal diameter of the sleeve 8 so that by pulling upward on the link 14 relatively to the sleeve 8, the plug 22 will partway enter the sleeve 8 and compress the rubber thereof into sealing engagement with the inner surface of the throat 9, as shown in Figures 2 and 3.

I provide a lever 24 which is preferably made of sheet metal first stamped in the form shown in Figure 5 and afterwards bent into the shape illustrated in Figures 1 to 4 inclusive. This lever has a central handle portion 25 and two wings 26. These wings are bent substantially parallel to each other and include curved cam edges 27 which terminate in fingers 28 at each side of a cut-out portion or recess 29. This recess 29 is arranged in line with the handle 25 and the fingers 28 are folded toward each other so that their outer edges 30 abut each other as shown in Figures 1 and 2. The wings 26, when the device is in its assembled position, are located adjacent opposite faces of the link 14 so that the fingers 28 extend through the yoked top 15 of the link with the side 17 of the link extending through the hole provided by the cut-out portion 29 of the lever 24.

The cam edges 27 are made convex from

the fingers 28 to the points or ends 31 and from the points 31 to the handle 25. The outer edge of the lever on each wing is made concave as shown in Figure 2. The cam edges 27 are adapted to rock on the top of the disk 12 and the fingers 28 engage the inner surface 33 of the yoked end 30 or they can be made to engage the under surfaces of the lugs 21 if a greater spreading 10 action is desired or if the nipple 7 is made shorter than that illustrated. In other words, the device is made to accommodate conditions of various characters so that the stopper can be made to seal container 15 throats of different characters.

When the stopper is to be attached, the parts are arranged in the positions shown in Figure 4; the sleeve being positioned within the throat of the bottle with the flange 10 in abutment with the top surface 11 thereof. In this position the plug 22 is below the nipple and the cam edges 27 engage the top surface of the disk. To seal the throat of the bottle the lever 27 is moved 25 so that the cam edges 27 will rock on the upper surface of the disk and the fingers 28 will pull the link upwardly until the plug 22 partway enters the lower end of the sleeve 8 and compresses said sleeve into 30 firm sealing engagement with the inner surface of the throat 9; the fingers 28 moving upwardly until the points 31 engage the disk 12, after which a continued downward movement of the handle 25 will cause the edge 32 to engage the disk as shown in Figure 3 and the points 31 to move into a position at the opposite side of a vertical plane passing downwardly through the fingers 28. In other words, the points 31 are moved to 40 a position off center and it is impossible for any expanding action of the rubber of the nipple to accidentally swing the handle upwardly after it once reaches the position shown in Figure 3. Thus the parts of the 45 nipple are held in firm sliding engagement with the inner surface of the throat of the bottle and also against the top surface 11 of the bottle neck.

The link, if desired, can be stamped out 50 of metal and it is obvious that the parts can be readily assembled or disassembled. For example the plug 22, when the nipple is out of the neck of the bottle, can be readily 55 detached from the hooked portion 16 by slightly expanding the lower end of the nipple and throwing the eyelet 23 over the upturned end 20 of the hooked portion. After the plug has been detached the link can be pulled out of the nipple and disk, and after this action the lever can be pulled 60 down along the side 18 of the link by first throwing the link over the hooked end 15 and when the fingers 28 reach the space 19 it will readily become detached from the link. It is thus an easy matter to replace 65

any of the parts such for example if it is desired to substitute a new rubber nipple.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A device for the purposes herein set forth comprising in combination with the throat of a bottle, a nipple having a sleeved portion adapted to be inserted in the throat of the bottle, means movable lengthwise in said sleeve and adapted to compress the sleeve, sealing the throat of the bottle, means for moving said sealing means, and means permitting adjustment of said moving means.

2. A stopper adapted to seal the throat of a container, including a flexible resilient sleeve for insertion within the throat of the container; a link extending within said sleeve; a spreading plug pivotally carried by said link; and means for moving said link relatively to the sleeve whereby said spreading plug will compress the sleeve into sealing engagement with the throat of the container and means permitting adjustment of said moving means to increase the compression of the sleeve; substantially as described.

3. A stopper adapted to seal the throat of a container, including a flexible resilient sleeve for insertion within the throat of the container; a link extending within said sleeve; a spreading plug carried by said link; and means for moving said link relatively to the sleeve whereby said spreading plug will compress the sleeve into sealing engagement with the throat of the container, said link having a hooked portion with a free end, said plug having an eyelet adapted to be hooked over said free end so as to hang on the link; substantially as described.

4. A device for the purposes herein set forth including in combination with the throat of a container, a member having a central passage mounted in the throat of the bottle, means for compressing said member to seal said throat, and adjustable means for moving said compressing means.

5. A stopper adapted to seal the throat of a container, including a flexible resilient sleeve for insertion within the throat of the container; a link extending within said sleeve; a member removably carried by the link for spreading engagement with said sleeve; and a lever having wing portions

providing fingers extending through the top of the link, said wings providing a cam for effecting the lifting of said link by said fingers to cause said spreading of the sleeve 5 by said spreading member; substantially as described.

6. A stopper adapted to seal the throat of a container, including a flexible resilient sleeve for insertion within the throat of 10 the container; a link extending within said sleeve; means carried by the link for spreading engagement with said sleeve; and a lever having wing portions providing fingers extending through the top of the 15 link, said wings providing a cam for effecting the lifting of said link by said fingers to cause said spreading of the sleeve by said spreading means, said link having lugs arranged at different levels for selective engagement with said fingers of the lever; substantially as described.

7. A bottle stopper comprising a resilient nipple having a hollow sleeve for insertion in the neck of the bottle; an open link extending within said sleeve and freely movable therein; a tapered spreading plug carried by said link and removable through the open portion thereof, and means for moving said link relatively to the sleeve whereby said plug will enter the bottom of the sleeve and compress the same outwardly into sealing engagement with the neck of the bottle.

8. A bottle stopper including a resilient sleeve for insertion in the neck of the bottle and having a circumscribing flange at one end to engage the mouth portion of the bottle; a tapered spreading plug disposed to enter the bottom of the sleeve and spread 40 the same outwardly against the neck; a disk of relatively stiff material resting upon the flange and having an opening

therein in line with the bore of the sleeve; a camming lever adapted to rock on the disk, and a connection between the camming lever and plug, comprising a link through which a portion of the lever extends, said lever being free of connection with the bottle and adapted when lowered to raise the link and plug whereby the latter will enter and exert outward pressure in the lower portion of the sleeve to retain the sleeve in the bottle neck and simultaneously force the disk against the flange to hold the latter against the mouth of the bottle neck and vice versa.

9. A bottle stopper including a resilient sleeve for insertion in the neck of the bottle and having a circumscribing flange at one end to engage the mouth portion of the bottle; a tapered spring plug disposed to enter the bottom of the sleeve and spread the same outwardly against the neck; a disk of relatively stiff material resting upon the flange and having an opening therein in line with the bore of the sleeve; a camming lever adapted to rock on the disk, and a connection between the camming lever and plug, said connection comprising a link having an opening at one side and having in the upper portion thereof, a series of engaging faces, and said lever comprising a folded blank straddling the link and having portions extending through the link to operate beneath said engaging portions, substantially as described.

In testimony whereof I have signed my name to this specification in the presence of two subscribing witnesses.

JOHN SCHEDLER.
